UNITED STATES PATENT OFFICE.

HAZEL N. PEDERSEN, OF RACINE, WISCONSIN.

UPHOLSTERED SEAT STRUCTURE.

1,306,619.

Specification of Letters Patent. Patented June 10, 1919.

Application filed November 21, 1917. Serial No. 203,156.

To all whom it may concern:

Be it known that I, HAZEL N. PEDERSEN, a citizen of the United States, and resident of Racine, county of Racine, and State of Wisconsin, have invented certain new and useful Improvements in and Relating to Upholstered Seat Structures, of which the following is a specification.

This invention relates to certain improvements in upholstered seat structures; and the objects and nature of the invention will be readily understood by those skilled in the art in the light of the following explanation of the accompanying drawings illustrating what I now believe to be the preferred mechanical expression or embodiment of my invention from among other forms, constructions and arrangements within the spirit and scope thereof.

An object of the invention is to improve the bottom frames of spring and other seats having top cushions wherein the seat or cushion cover depends in the form of an apron and at its lower edge is secured to or by such bottom frames.

A further object of the invention is to provide a bottom frame for such seats whereby the cover apron can be quickly and easily secured, in the process of applying the seat cushions and cover to the spring structure, and whereby the portion of said cover, where joined to the frame, will be guarded and protected by the formation of said frame.

A further object of the invention is to provide a bottom frame that will constitute the bottom supporting rim of the seat structure as well as the bottom stiffening frame to which the lower ends of the outer springs are secured, and that comprises co-operating clamping members constructed to fit one within the other and clamp and securely fasten the lower edge of the cover apron.

A further object of the invention is to provide a spring seat structure, adapted to be upholstered, with a bottom frame comprising upper and lower interfitting members adapted to clamp and secure the lower edge of the seat cover apron, said members being so formed that channel iron or the like, similar in cross section can be utilized in the formation of both members.

With these and other objects in view the invention consists in certain novel features in construction and in combinations and arrangements as more fully and particularly set forth and specified hereinafter.

Referring to the accompanying drawings:

Figure 1, is a perspective view showing a bottom and corner portion of an automobile or other upholstered spring seat, some of the coiled springs being shown.

Fig. 2, is a detail sectional view.

Fig. 3, is a sectional detail of certain parts shown in abnormal positions separated from each other.

In seats of this type, a spring structure is employed comprising series of vertically-disposed coiled or volute springs, such as 1, and these springs are suitably coupled together at their upper ends and secured to or within an upper frame, and the lower ends of the springs are also coupled together and secured to or within a lower frame. Suitable upholstering, such as 2, is secured on the spring structure, and this upholstering usually includes cushions on the spring structure, and a suitable leather or other covering and this covering includes a flexible apron arranged vertically at the sides or edges of the spring structure to cover or inclose the same between the upper and lower frames of the spring structure.

The present invention relates particularly to the bottom frame of the spring structure and to the formation thereof for securing the lower edge of the depending cover apron and for other purposes.

In the specific embodiment illustrated, this bottom frame forms the bottom supporting or depending rim of the seat adapted to rest on the seat support and carry the weight of the seat and its occupant, and this rim is composed of an upper member, frame or section and a complementary lower member, frame or section receiving the upper member and the lower edge of the cover apron. The upper member consists of a metal strip or bar having a depending vertical flange and a top longitudinal channel or socket 4, open at its inner edge or side, at 5, and having horizontal approximately flat parallel upper and lower walls joined by a vertically disposed rounded curved portion 6 forming the outer edge or side of the metal strip or bar and rendering the channel thereof of approximately U-shape in cross section. The horizontal bottom wall of the channel is continued downwardly from the open edge of the channel to form the depending approximately flat vertical longitudinal wall or flange 7. The channel formation of this

longitudinal strip or member not only stiffens and strengthens the same, but also provides means for receiving and securing the same to the edge or outer coiled springs of 5 the spring seat structure. For instance, I show the outer portions of the bottom or lower end convolutions of these springs fitted snugly in the channel or socket of said member and said member and spring convolutions are permanently secured and coupled together by pinching the free edge portion of the top wall of the channel downwardly, at 8', to embrace or partially embrace the wires forming said convolutions. 10

15 The complementary lower frame or member of the rim consists of a metal bar or strip forming an outwardly extending horizontally disposed longitudinal flange 8 and a vertically-disposed longitudinal channel or 20 socket 9, open at its top edge or side and having approximately parallel vertical side walls with the flange 8 extending laterally and outwardly from the upper edge of the outer wall of the channel. In what I now 25 believe to be the preferred form of my invention, the two frames or members of the rim are similar in cross section and can be composed of similar channel strips bent or rolled by the same dies or other machine. 30 The lower member of the rim is so formed and arranged with respect to the other member, that the flange 7 of the upper member will enter the channel 9 of the lower member to form an apron retaining clip or clamp, 35 and the out turned flange 8 of the lower member will underlie the bottom wall of the channel 4 of the upper member and form a guard for the portion of the apron where it enters the rim, and if need be the flange 8 and lower wall of channel 4 will coöperate 40 to clamp the apron and limit the relative interlocking or intermeshing movement of the two members.

In applying the rim, the upper frame is 45 arranged around the exterior of the lower end or portion of the spring structure and secured to the lower ends of the springs as described, with the cover apron 3 arranged at the exterior thereof or inclosing the same. 50 The lower edge or free portion of the apron is then folded inwardly across the said upper member and its flange 7, and the lower member is then applied so that the lower edge of the apron will be clamped between 55 the two members. When the two members have been forced tightly together to operative position and the seat is in normal upright position, the apron extends down at the exterior of the rounded outer edge 6 of 60 the upper member and inwardly along the bottom surface of the lower wall of channel 4 and forms a bight in the channel 9, facing both vertical faces of the flange 7. The flange 7 in effect forms a key or wedge

whereby the apron is forced down in channel 9 under pressure and is therein wedged and locked. The material of the channel is more or less resilient and the walls of the channel are usually slightly sprung apart by the action of forcing the apron thereinto and hence the resilient action of the channel tends to more tightly grip and clamp the apron. 65 70

The flange 8, of the lower member, also coöperates with the horizontal channel portion of the upper member to clamp the horizontal inwardly extending portion of the apron, and furthermore acts as a stop limiting the intermeshing movement of the two members to prevent the lower edge of flange 75 80 approaching so close to the floor of channel 9 as to wear through or sever the apron along that line.

The outwardly projecting flange 8, in the completed rim, also serves as a guard for 85 protecting the portion of the apron engaging the rounded surface 6 of the rim, against wear and injury through contact with adjacent parts when in use. The rounded surface 6 also serves to reduce to the minimum 90 wear and breakage of the apron along the line where it bends to enter the rim.

The weight of the seat and its occupant, tends to force and hold the two members together in operative apron gripping adjustment, and furthermore these members are held together by reason of the fact that the apron is tightly wedged and forced under tension in channel 9 by locking key or flange 7. 100

If so desired, suitable clips can be employed to prevent possibility of accidental separation of the rim members during handling and shipment, but such clips are not essential and I do not wish to limit my invention to the employment thereof. 105

In the specific example illustrated, each clip is formed by a sheet metal strip or plate having a flat vertical body portion 10 arranged at the inner vertical side of the rim, a laterally or outwardly extending upper end 11 in the form of a hook bill extending transversely across the top side of the upper member of the rim and engaging the rounded outer edge 6 thereof, and a lower end 12 110 extending outwardly across the lower edge of channel 9 and bent upwardly at the outer vertical side of said channel. These clips can be formed before application, as shown 115 by Fig. 3, with the lower end 12, straight. The clips can be applied to the completed rim, from the inside by hooking their ends 11 over the top edge of the rim and then swinging the clips outwardly against the inner vertical wall of channel 9, and then bending the free outer ends of ends 12 upwardly to fasten the clips. The clips can be 120 opened or unlocked for release, to permit 125

separation of the members of the rim, by bending their outer ends 12 downwardly, as will be readily understood.

Those skilled in the art will appreciate 5 the advantages of a rim that can be thus quickly applied to firmly grip and hold the cover apron without puncturing the same and without the use of extra or separate cover fastening devices.

10 It will also be noted that the rim is exceedingly stiff and rigid, and in the specific example illustrated, embodies three metal layers or thicknesses both vertically and transversely, and also embodies channels 15 both vertically and horizontally, although as at present advised, I do not wish to so limit all features of my invention.

It is evident that various changes and modifications might be resorted to without 20 departing from the spirit and scope of my invention and hence I do not wish to limit myself to the exact disclosures hereof.

What I claim is:—

1. In spring seat construction, a depending seat supporting and cover apron clamping bottom rim comprising a pair of longitudinally channeled and flanged complementary members, the flange of one member arranged to clamp the apron in the channel 30 of the other member, and the flange of said other member arranged to form an exterior outwardly projecting apron guard.

2. In spring seat construction, a bottom spring securing and cover apron clamping 35 frame comprising complementary intermeshing flanged channel members, the channel of one member formed to overlie the flange of the other member and having a depending flange to enter the channel of said other 40 member.

3. In spring seat construction, a bottom rim comprising a top member having a channel to receive portions of seat spring convolutions, a wall of said channel formed 45 to be pinched at intervals to partially embrace said portions, and a bottom member having a flange to guard the cover apron, said rim members embodying an apron receiving channel and a flange for locking 50 and wedging the apron in the channel.

4. In spring seat construction, a bottom seat supporting and cover-apron securing rim embodying longitudinally flanged and channeled complementary members substantially similar in cross section.

5. In spring seat construction, a seat supporting and cover-apron securing rim comprising a lower member having a vertically-disposed open-top longitudinal channel, and 60 a complementary upper member having a depending longitudinal locking-key-forming portion for wedging and gripping the apron in said channel, said members having opposing coöperating surfaces for clamping said 65 apron at the exterior of said channel.

6. In spring seat construction, a cover apron securing rim comprising upper and lower complementary members between which the apron is clamped, said members providing a vertically-disposed longitudinal 70 apron receiving channel and a vertically-disposed longitudinal key for forcing the apron into and wedging the same in the channel, said members also providing opposing longitudinal transverse surfaces between 75 which the apron extends and by which the vertical intermeshing movement of the channel and key is limited.

7. In spring seat construction, a seat supporting and cover-apron clamping rim comprising a longitudinal member having a horizontal spring-convolution-receiving and securing channel and a longitudinal flange depending at the inner edge of said channel, and a longitudinal member having a vertical longitudinal apron-receiving channel adapted to receive and coöperate with said flange in clamping and securing the apron in the channel, said last mentioned member having a horizontal longitudinal flange projecting outwardly from the outer wall of its channel to guard the apron and underlie the portion thereof transversely of the bottom surface of said horizontal channel of the upper member. 95

8. A border strip for spring seat constructions, comprising a channel portion, a flange depending therefrom, and a clamping element adapted to be applied to said flange.

9. A border strip for spring seat construction, comprising a channel portion adapted to receive the springs of said construction, a flange depending from said channel portion for receiving the depending ends of seat covering material, and a spring clamping element adapted to be forced over said flange and the material thereon to bind the same thereto. 100

10. A border strip for spring seat construction, comprising a single piece of material formed with a channel portion and a portion extending from one side thereof to form a flange, and a U-shaped spring clamping element adapted to be forced over and onto said flange. 110

11. A spring seat construction, comprising a series of coiled springs, a border strip extending therearound to which said springs are fastened, a flange portion depending from the border strip, seat covering material 120 on said construction and depending downwardly over the sides thereof, the ends of said material passed over said flange, and a resilient clamping channel forced over the material and the flange and removably binding the material to the flange. 125

12. A spring seat construction comprising a series of coil springs, a border strip comprising a channel portion adapted to receive convolutions of said springs, a flange 130

portion extending from said channel portion, one side of said channel portion bent over the convolutions of said springs fastening the same therein and thereto, and a 5 clamping element adapted to be applied to the flange portion of said border strip whereby covering material may be bound to said construction.

13. In spring seat construction, a bottom 10 spring frame comprising a horizontally arranged channel having a depending flange, and a vertically arranged channel having an out turned flange, said vertical channel adapted to be forced upwardly on said depending flange with the edge portion of the 15 apron intervening between the channel and said flange and between said out turned flange and said horizontal channel.

14. In spring seat construction, a bottom 20 spring frame comprising a member having a horizontally disposed channel open at its

inner edge to receive and secure the bottom convolutions of the outer springs, the apron of the seat adapted to pass down at the outer side of and inwardly beneath said member, and a separate clamping element securing the apron to the under side of said member and facing the apron below said member. 25

15. In spring seat construction, a bottom spring frame comprising an upper member 30 secured to the springs and having a depending flange and an upper outwardly extending shoulder, the seat apron adapted to extend down at the outer side of said member and inwardly under said shoulder and 35 around said flange, and a clamping channel adapted to clamp said apron against said flange and having an out turned flange adapted to coöperate with said shoulder in clamping said apron.

HAZEL N. PEDERSEN.
